US00D853063S

(12) **United States Design Patent** (10) **Patent No.:** **US D853,063 S**
Johnson (45) **Date of Patent:** **** Jul. 2, 2019**

(54) **SURFACE CLEANING HEAD WITH DUAL ROLLERS**

(71) Applicant: **SHARKNINJA OPERATING LLC**,
Newton, MA (US)

(72) Inventor: **Owen R. Johnson**, Needham, MA (US)

(73) Assignee: **SharkNinja Operating LLC**,
Needham, MA (US)

(**) Term: **15 Years**

(21) Appl. No.: **29/605,401**

(22) Filed: **May 25, 2017**

(51) LOC (11) Cl. **15-05**

(52) U.S. Cl.

USPC **D32/33**

(58) **Field of Classification Search**

USPC D32/31-34, 20-22, 38-39, 45
CPC A47L 9/02; A47L 9/04; A47L 9/06; A47L 9/0477; A47L 9/2842; A47L 9/0693; A47L 9/0444; A47L 9/0461; A47L 9/325; A47L 9/28; A47L 5/362; A47L 5/365; A47L 5/325; A47L 5/28; A47L 5/30; A47L 5/34; A47L 5/36; A47L 5/02; A47L 5/24; A47L 11/4044; E04H 4/1654; A46B 13/001; E01H 1/0854

(57) **CLAIM**

The ornamental design of a surface cleaning head with dual rollers, as shown and described.

DESCRIPTION

FIG. 1 is a perspective view of a surface cleaning head with dual rollers showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

1 Claim, 8 Drawing Sheets
